(57) **CLAIM**

The ornamental design for an electronic camera, as shown and described.

DESCRIPTION

FIG. 1 is a front perspective view of an electronic camera showing our new design;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof;

FIG. 8 is a front perspective view of an alternate embodiment of the electronic camera showing our new design;

FIG. 9 is a front view thereof;

FIG. 10 is a left side view thereof;

FIG. 11 is a rear view thereof;

FIG. 12 is a right side view thereof;

FIG. 13 is a top view thereof; and,

FIG. 14 is a bottom view thereof.

The broken line showing of various regions in the FIGS. 1 and 3-7, including the unshaded areas therein, is for illustrative purposes and forms no part of the claimed design.
